United States Patent Office

Des. 222,591
Patented Nov. 9, 1971

222,591

WHEEL CHOCK

Joseph F. Steinke, Brandon Road, Rte. 4,
Joliet, Ill. 60436

Filed June 22, 1970, Ser. No. 23,607

Term of patent 14 years

Int. Cl. D12—16

U.S. Cl. D41—1

Fig. 1.

Fig. 2.

Fig. 3.

FIG. 1 is a side elevational view of a wheel chock embodying my new design;

FIG. 2 is a top plan view looking downwardly toward FIG. 1;

FIG. 3 is an end elevational view looking toward the right-hand end of FIG. 1.

The right- and left-hand end elevational views of FIG. 1 are the same as FIG. 3, merely reversed in position; and

The rear elevational view is the same as shown in FIG. 1.

I claim:

The ornamental design for a wheel chock, as shown and described.
